UNITED STATES PATENT OFFICE

2,513,479

AMBULANCE COT COVER

Dorothy M. Harbaugh, Mansfield, Ohio

Application November 25, 1947, Serial No. 787,963

1 Claim. (Cl. 135—5.2)

1

This invention relates to improvements and structural refinements in covers for cots or stretchers, particularly those used in ambulances, and the principal object of the invention is to provide a device of the type herein described, such as may be conveniently and effectively employed in association with such cots or stretchers for the purpose of protecting the person thereon from excessive heat, cold, or other adverse atmospheric conditions.

A further object of the invention is to provide a cot cover which is of an extensible and collapsible nature, so to speak, so that it may be easily folded and stored when it is not being used.

Another object of the invention is to provide a cot cover which is simple in construction, pleasing in appearance and which will not interfere to a great extent with the placing of a person upon the cot, and similarly, the removal of such person from the cot.

An additional object of the invention is to provide the cot cover which will readily lend itself to economical manufacture and which is otherwise well adapted for the purpose for which it is intended.

With the above more important objects in view and such other objects as may become apparent as this specification proceeds, the invention consists essentially of the construction and arrangement of parts as shown in the accompanying drawings in which:

Figure 1 is a perspective view of the invention in its extended position.

Figure 2 is a perspective view thereof in a collapsed position.

Figure 3 is a longitudinal cross sectional view of the cover shown in Figure 1.

Figure 4 is a cross sectional view, taken substantially in the plane of the line 4—4 of Figure 3.

Figure 5 is a perspective view of the modified form of the invention, the same being shown extended, and

Figure 6 is a perspective view of the cover shown in Figure 5, but illustrating the same as being collapsed.

Like characters of reference are employed to designate like parts in the specification and throughout the several views.

Referring now to the accompanying drawings in detail, more particularly to Figures 1-4, inclusively, the invention consists of a cot cover designated generally by the reference character 10, the same being invented for use with a conventional ambulance cot or stretcher indicated by the phantom lines 11.

2

The cover 10 embodies in its construction a longitudinally extensible and collapsible frame 12 which includes a pair of side members 13 and a plurality of cross bars 14, each of the side members 13 being formed by a series of crossed metal straps 15, 16, which are pivotally connected together as at 17 and 18.

The cross bars 14 are provided with angulated end portions 19 which are attached to the straps 15, 16 by some of the pivots 18, whereby the two side members 13 are secured together and held in spaced parallel relation, as will be clearly apparent from the accompanying drawings.

It will be noted that the straps 16 are somewhat longer with respect to the straps 15, whereby one end portion of the frame 12 is relatively enlarged, this of course, being adapted to accommodate the head of the occupant of the cot or the stretcher.

20 A jacket 20 formed from fabric or from some other flexible material covers the frame 12, the jacket including a pair of side walls 21, a continuous top and end wall 2, and a continuous foot panel, top wall portion and face shield 23.

25 Suitable fastening means, such as for example, snap-on fasteners 24 are employed for separably attaching the various wall members of the jacket 20 to the frame 12, the fasteners 24 being preferably positioned at the upper ends of the straps 15, 16 in coincidence with the pivot connections 18. Moreover, further fasteners 25 may be used for attaching the foot portion of the wall member 23 to the frame, while additional fasteners 26 are used for similarly attaching the face panel 30 portion of the wall member 23 to the top wall member 22, as will be clearly apparent.

As is best shown in Figures 1 and 3, the face panel portion of the wall member 23 is provided with a transparent panel 27 for the convenience of the patient and also, to facilitate observation of the patient by the attendant.

The end straps of the frame 12 are equipped with suitable hooks 28 which extend downwardly from the frame and are adapted to separably engage the cot or stretcher 11, whereby the entire cover is held in position on the cot.

When the invention is placed in use, the cover is extended as shown in Figures 1 and 3 and is fastened to the stretcher or cot 11, by means of the hooks 28, whereupon after unfastening the wall member 23, the patient may be applied to or removed from the stretcher with convenience.

When the invention is not used it may be simply detached from the cot or stretcher and collapsed in an accordion fashion as shown in

Figure 2, which, of course, is facilitated by the provision of the extensible and collapsible frame 12 as will be readily appreciated.

Referring now to the modified embodiment of the invention as shown in the accompanying Figures 5 and 6, the same is designated generally by the reference character 40 and is adapted for use in association with a conventional stretcher or cot 41 already equipped with a hood 42.

In this instance, the structure of the cover 40 is substantially similar to that of the cover 10, but the cover 40 is not enlarged at one end thereof since the hood 42 is already provided on the stretcher.

However, the cover 40 does include in its construction a face panel 43 equipped with a transparent "window" 44, this panel being intended to fit the hood 42, substantially as shown.

The cover 40 as well as the face panel 43 are separably attached to the cot by any suitable fasteners, as exemplified in the accompanying drawings by the snap-on fasteners 45 and by a slide fastener 46. As will be observed, the face panel 43 including "window" 44 may be rolled up as shown in Figure 6 when the cover is collapsed.

It is believed that the advantage and use of the invention will be clearly apparent from the foregoing disclosure and accordingly, further description thereof at this point is deemed unnecessary.

While in the foregoing there has been shown and described the preferred embodiment of this invention it is to be understood that minor changes in the details of construction, combina-

tion and arrangement of parts may be resorted to without departing from the spirit and scope of the invention as claimed.

Having described the invention, what is claimed as new is:

In an ambulance cot cover, the combination of a frame including a pair of spaced parallel side members each consisting of pairs of crossed straps pivoted together at their points of crossing, the straps in each pair having free lower ends pivotally connected to corresponding ends of the straps in adjacent pairs, a set of cross members extending between said side members, pivot elements connecting the ends of said cross members to free upper ends of said straps and connecting the upper ends of the straps in one pair to the corresponding ends of the straps in adjacent pairs, and a jacket of flexible material secured to and covering said frame, the straps at one end of said frame being longer than the remaining straps whereby an end portion of the cover is substantially enlarged.

DOROTHY M. HARBAUGH.
